ATTORNEY'S.

UNITED STATES PATENT OFFICE.

WILLIAM H. PUTNAM, OF ROME, NEW YORK.

DESIGN FOR AN ALPHABET FOR SIGN-LETTERS.

SPECIFICATION forming part of Design No. 23,533, dated August 7, 1894.

Application filed June 29, 1894. Serial No. 516,126. Term of patent 3½ years.

To all whom it may concern:

Be it known that I, WILLIAM H. PUTNAM, a citizen of the United States, residing in the city of Rome, Oneida county, New York, have 5 invented and produced a new and original Design for an Alphabet for Sign-Letters, of which the following is a specification, reference being made to the accompanying drawing, forming a part hereof.

10 The drawing shows an alphabet of letters of my design.

The leading features of my letters, or the distinguishing peculiarities, are the ears or tabs *a* on the ends and corners of the letters, 15 which ears or tabs are substantially squarely cut off at their outer ends, and a stubby point *b* on the middle portion of what would otherwise be a long straight line of the letter.

The face of the letter is rounded; the

rounded portions being carried on to the projection or tab *a* and up to the points *b*, giving the letter a thickened heavy appearance. By providing the point *b* projecting from the portions of the letter which would otherwise be long straight lines, the long straight lines 25 are converted into two or more curved lines, which adds to the solid heavy appearance of the letter, as before stated.

What I claim is—

The design for an alphabet of sign letters, 30 substantially as shown and described.

In witness whereof I have affixed my signature in presence of two witnesses.

WILLIAM H. PUTNAM.

Witnesses:

C. D. PRESCOTT,
CHARLES T. TITUS.
